UNITED STATES PATENT OFFICE.

ANTONIO C. PESSANO, OF PHILADELPHIA, PENNSYLVANIA, ASSIGNOR TO
THE GEO. V. CRESSON COMPANY, OF PENNSYLVANIA.

VERTICAL-SHAFT BEARING.

SPECIFICATION forming part of Letters Patent No. 514,684, dated February 13, 1894.

Application filed October 28, 1893. Serial No. 489,381. (No model.)

To all whom it may concern:

Be it known that I, ANTONIO C. PESSANO, a citizen of the United States, residing in the city of Philadelphia, State of Pennsylvania, 5 have invented a new and useful Improvement in Vertical-Shaft Bearings, of which invention the following is a specification.

My invention consists of an adjustable step-bearing for vertical shafts, the object in view 10 being, by simple devices, to practically free the shaft from undue friction, and to render the interior of the step-box accessible for purposes of examination, adjustment, removal, or repair of the parts therein contained without the necessity of removing the whole box or of jacking up the shaft further than simply 15 to relieve the step of the shaft's weight.

In the annexed drawings, Figure 1 is a side elevation of the bearing, including a portion 20 of a vertical shaft. Fig. 2 is a plan of the same. Fig. 3 is a vertical section of the same on the line α , α of Fig. 2, the shaft being in elevation. Figs. 4 and 5 are perspective views of either of the two similar anti-friction plates 25 or washers o , showing the two opposite channeled faces of the respective plates. Fig. 6 is a perspective view of the collar j inverted. Fig. 7 is a vertical section on the line α , α in Fig. 2 of the two-parted chambered covering 30 plate t showing the packing-chamber and the dove-tail or dust excluding joint by which the two parts of the plate come together.

Similar letters of reference denote similar parts in the several figures.

35 a represents the bed-plate which is intended to be secured to the floor or foundation; as by bolts at b , Fig. 2. The bed-plate is shown to be provided with a ledge c . Integral with the bed-plate are the three upright sides d , e , f , Fig. 2 of the step-box. One side of this box consists of the removable plate g , which is fastened with screw-bolts to the permanent portions of the step-box, lead packing or other metallic packing being used to make a tight 40 joint. The inner sides of the step-box are provided with the lugs i for giving loose lateral support to the collar j . Collar j is provided with the bearing lugs k , Fig. 6, and the oil-channels m . The lugs k bear directly on 45 the margin of the upper or flat face of the rocker n . The rocker n is preferably made 50

of hardened steel, having octagonal, square or other rectilinear contour, and its lower or convex face rests loosely in the flat-bottomed recess n' of corresponding form, in the bottom 55 of the step-chamber, as shown in Fig. 3.

o represents two similar flat anti-friction plates or washers, each provided with radial oil-channels q on their respectively opposite faces and with an oil duct or aperture r . 60

The plates o fit loosely in the bore of the collar j , which holds these plates in position; one of the plates o resting on the upper or flat surface of the rocker n and the other plate o in turn resting on the first mentioned plate o . 65

s represents a vertical shaft passing with a loose fit through a hole in the covering plate t of the step-box. The shoe u of shaft s consists of phosphor-bronze or other anti-friction composition metal shrunk on foot s' of the 70 shaft, and it bears flatly on the upper face of the uppermost plate o . The foot s' is given a square or other rectilinear form in cross-section to prevent the shoe from turning on it.

y is a pipe with faucet for drawing off the 75 oil from chamber h .

The covering plate t is made in two parts which come together with a dovetail joint as shown in Fig. 7, and the hollow or chamber t' of this plate is intended to be filled with packing. Plate t when in position on the step-box, makes chamber h practically dust tight. 80

The step-box chamber h is supplied through the screw-closed oil hole v Fig. 2, with oil, which flows through the channels and ducts of the 85 collar and anti-friction plates, keeping the shoe of the shaft and the several operative parts inclosed in the step-box lubricated.

In case it becomes necessary to inspect, adjust, or remove the operative parts inclosed in 90 the step-box, easy access thereto is obtained by simply loosening the bolts of plate g and removing this plate.

When it is desired to surround the step-box with a water-jacket, as an additional precaution against the heating effect of friction, the bed-plate a is provided with the ledge c as shown, thus forming the water space w . In other cases this ledge can be omitted. 95

I have shown and described the use of two 100 flat anti-friction plates o , and I prefer to use this number, but good results are obtained

from the use of a single plate or of a greater number than two.

I claim—

For vertical shafts, an adjustable step-bearing, consisting first of a base plate, second a rectilinear step-box partly integral with the base plate, provided with a removable side *g* with a two-part packing chambered cover *t*, and with a flat bottomed recess *n'* having rectilinear walls, third a rocker *n* having correspondingly rectilinear sides, a flat or upper

surface and a convex or lower surface, said rocker fitting loosely in recess *n'*; fourth one or more flat anti-friction plates *o* interposed between the shoe *u* of the shaft and the flat 15 or upper face of rocker *n*, and fifth the collar *j*, substantially as set forth.

ANTONIO C. PESSANO.

Witnesses:

J. E. SHAW,
JOS. B. WILLITS.

It is hereby certified that the assignee, "the Geo. V. Cresson Company," in Letters Patent No. 514,684, granted February 13, 1894, upon the application of Antonio C. Pessano, of Philadelphia, Pennsylvania, for an improvement in "Vertical Shaft-Bearings," should have been described and specified as *Geo. V. Cresson Co.*, instead of "the Geo. V. Cresson Company"; and that the said Letters Patent should be read with this correction therein that the same may conform to the record of the case in the Patent Office.

Signed, countersigned, and sealed this 27th day of February, A. D. 1894.

[SEAL.]

JNO. M. REYNOLDS,

Assistant Secretary of the Interior.

Countersigned:

JOHN S. SEYMOUR,

Commissioner of Patents.
